R. M. STOLWORTHY

EXTENSION LADDER

Filed Mar. 16, 1922

INVENTOR:
Richard M. Stolworthy
BY
Albert Allen
ATTORNEYS.

UNITED STATES PATENT OFFICE.

RICHARD M. STOLWORTHY, OF CINCINNATI, OHIO.

EXTENSION LADDER.

Application filed March 16, 1922. Serial No. 544,071.

To all whom it may concern:

Be it known that I, RICHARD M. STOLWORTHY, a citizen of the United States, and a resident of Cincinnati, in the county of 5 Hamilton and State of Ohio, have invented certain new and useful Improvements in Extension Ladders, of which the following is a full, clear, and exact description, reference being had to the accompanying drawings, forming part of this specification.

My invention relates to ladders provided with an extension section especially adapted for use inside of buildings, and it consists of a construction in which the ladder may be 15 readily and easily extended and wherever located may be held in upright position by devices adapted to engage the ceiling of the room, so as to effectively support the weight of the user without liability of upsetting.

20 The invention consists of that novel construction and arrangement of parts to be hereinafter particularly pointed out and claimed, whereby the above results are attained.

25 In the drawings,

Figure 1 is a perspective view of my improved ladder.

Figure 2 is a longitudinal section of one 30 of the side rails of the vertical extension portion of the ladder.

Figure 3 is a cross section of one of these side rails.

The lower portion of the ladder is made 35 up of two sections A and B inclined towards each other to form a substantial support for the vertical section C.

The lower sections are formed in the usual way of side rails 1, 1, and 2, 2, with rungs 40 3 a convenient distance apart. The upper ends of the lower sections are provided with metal caps 4, 5, to reinforce and protect these ends, and each cap has a projecting lug 6, which is threaded to receive a clamping screw 7 operated by handle 8 to effect- 45 ively clamp the side rails 9 and 10 of the vertical extension section C.

The metal cap pieces are formed to overlap these side rails so that a firm and rigid 50 lock may be obtained when the clamp screws are tightened or the contracting clamping surfaces may be roughened or reinforced with ordinary toothed plates to more effectively accomplish this result. The side rails 9 and 10 of the vertical adjustable section C 55 have rungs 12 and for raising the vertical

section I provide a windlass 13 journaled in the side rails of one of the lower sections. This windlass has the handle 14 and a pair of cables 15 run from this windlass to be secured around a rung of the extension, so 60 that by loosening the clamp screws 7 and turning the windlass, the ladder can be raised or extended as desired. The lower and upper ends of the side rails of the section C are also protected with metal caps 65 16, 16, and 17, 17 respectively.

Extending upwardly either along the outside or preferably as illustrated through a longitudinal central opening in the side rails 9 and 10 is an elevating rod 18 for 70 each side rail, screwthreaded in the lower cap 16 and provided with a handle 19 for adjustment. The upper end of each elevating rod projects through the metal cap 17 and is provided with an adjusting sleeve 20 75 in which is mounted an adjusting screw 21. Each of these screws carries a vacuum cup 22 moulded or otherwise secured thereto, which cup is adapted to engage the ceiling 80 of the room in which the ladder is used in order to hold the ladder rigidly in place.

There is also provided with the ladder a pair of platform pieces 23, 23, provided with horizontal braces and hooks 24 to be engaged around any desired rung of the extension. These platforms are provided with supporting side chains 25 with hooks 26 to engage over an upper rung to hold the platform in horizontal position. In order to brace and support the members of the lower 90 sections A and B from spreading, I provide a keeper bar 27 and when desired hook rods 28 can also be employed at the lower end of the sections.

The use of the ladder will be obvious from 95 the foregoing description. A great advantage of the construction is that it can be used in any portion of the room desired, the extension C being raised as described nearly to the ceiling and the vacuum caps then 100 elevated by the rods 18 until they obtain a firm grasp on the ceiling.

It will also be obvious that two or more of the ladders can readily be employed to form a scaffold with platform boards resting 105 on the rungs.

Having thus described my invention, what I claim as new and desire to secure by Letters Patent, is:

1. In an extension ladder for interior use, 110

the combination with supporting base sections, of a vertical section, with means for extending and clamping the vertical section upon the supporting base, the side rails of the extension section being provided with 5 vacuum cups to engage the ceiling to secure the ladder in vertical position.

2. In an extension ladder for interior use, the combination with supporting base sections, of a vertical section, with means for extending and clamping the vertical section upon the supporting base, the side rails of the extension section being provided with 10 vacuum cups to secure the ladder in vertical position, and means for extending said cups 15 to engage the ceiling.

3. In an extension ladder for interior use, the combination with supporting base sections, of a vertical section, with means for

extending and clamping the vertical section 20 upon the supporting base, the side rails of the extension section being provided with elevating rods, and means for operating them, the upper ends of the rods carrying vacuum cups to engage the ceiling. 25

4. In an extension ladder for interior use, the combination with supporting base sections, of a vertical section, with means for extending and clamping the vertical section upon the supporting base, the side rails of the extension section being provided with 30 longitudinal openings, elevating rods extending through said openings, with handles at the lower ends for operating them, the upper ends of the rods carrying vacuum cups to 35 engage the ceiling.

RICHARD M. STOLWORTHY.
